X-RAY APPARATUS

John Thomas Caldwell, Sudbury, Wembley, England, assignor to The General Electric Company, Limited, London, England

Application April 8, 1947, Serial No. 740,025
In Great Britain February 6, 1946

Section 1, Public Law 690, August 8, 1946
Patent expires February 6, 1966

10 Claims. (Cl. 250—87)

1

This invention relates to X-ray apparatus and more particularly, but not exclusively, to X-ray apparatus for deep therapy.

The invention is more particularly concerned with deep therapy apparatus adapted to operate at about 220 kv. Deep therapy apparatus arranged to operate at this voltage at present in use may be divided into two general types. One type includes apparatus in which a shockproof tube, that is, an X-ray tube in which there is protection against electrical shock to the user, is connected by way of cables to a high tension generator. The other type includes apparatus in which a shockproof head is provided containing both an X-ray tube and a high tension transformer, the X-ray tube itself generally serving to rectify the transformer output.

Both types of apparatus suffer from certain disadvantages. Thus, in the case of the first type, the relatively inflexible high tension cables feeding the supply to the tube in its shockproof enclosure tend to impede orientation of the tube and give the apparatus an untidy appearance.

In the case of the other type, the head is necessarily somewhat heavy and bulky and tends to have a bad psychological effect on the patient receiving treatment. In addition, precise positioning with respect to the part to be treated is difficult, necessitating, for best results, some controlled motive means such as electric drives. Additionally, since in the interests of size and weight it is usual to energise the X-ray tube direct from the transformer, the tube is generally of the self-rectifying type. Such tubes are usually limited in output and the operating conditions are much more strenuous than when the tube is energised from a rectified supply of high tension, with consequent effect on tube life.

One object of the present invention is the provision of deep therapy apparatus in which the disadvantages set out above are minimised.

According to the present invention, in X-ray apparatus more particularly, but not exclusively, for deep therapy a movable shockproof head is supported in a suitable manner on a pedestal or the like and the head forms a housing for an X-ray tube and electrical equipment arranged to generate a substantial portion of the operating voltage required by the tube, the electrical equipment arranged to generate the remaining portion of the said voltage being physically separate from the head.

Thus, the operating voltage may be generated partly by a D. C. generation equipment physically separate from and external to the head

2

and partly by high tension transformer equipment mounted within the head.

The head may be so mounted on the pedestal or the like for vertical movement up and down and the weight of the head may be substantially balanced by the weight of the D. C. generation equipment. Both the high tension transformer equipment and the D. C. generation equipment may each be divided into two parts preferably equal, one part of each being associated with the cathode of the X-ray tube and the other part of each with the anode of the tube.

One form of deep therapy X-ray apparatus in accordance with the present invention and arranged to operate at a peak voltage of 220 kv. will now be described by way of example, with reference to the four figures of the accompanying drawings. In the drawings Figure 1 shows a perspective view of the pedestal and X-ray head, Figure 2 is a partly diagrammatic drawing of the X-ray head and its ancillary equipment in the pedestal, Figure 3 is a diagrammatic drawing of the electric circuit of the arrangement in the pedestal and Figure 4 shows a view of the pedestal as in Figure 1 with part of the outside casing removed.

Referring now to Figure 1 of the drawings, the apparatus comprises a pedestal 1, supporting a movable shockproof head 2, and an associated control desk (not shown). The desk is arranged in known manner with kilo-voltage control, filament voltage control, timing control and shutter control and is connected to the pedestal 1 by means of suitably insulated cables (not shown). The pedestal 1 which supports the shockproof head 2 also houses the D. C. generation equipment.

Referring now to Figure 2, the X-ray tube 3 is mounted in the head 2 together with two separate high tension transformers 4 and 5 each arranged to provide a peak voltage of 50 kv. on load and a filament transformer 27 arranged to supply the filament of the X-ray tube 3. The head 2 which comprises a steel tank 6 with a removable lid 7 having a suitable window 8, is oil-filled and oil is continuously circulated through the head 2 by means of a pump 9 supported by the pedestal 1 (in Figure 1). The oil is cooled by a cooler 10 also supported by the pedestal 1 (in Figure 1) and the oil is supplied to and removed from the head 2 by way of flexible tubing 11 and 12. The oil is actually supplied direct to the hollow anode 13 of the X-ray tube 3 in the head 2 and passes out of the anode 13 into the head 2 so that the X-ray tube

3 and the transformers 4, 5 and 27 are completely surrounded by oil. The head 2 is divided into two parts by a central partition 14 of insulating material, and on one side of the partition 14, the X-ray tube 3 is supported, and on the other side, the transformers 4, 5 and 27.

The X-ray tube 3 is mounted within an X-ray protective enclosure of lead alloy or other protective material of a conductive nature. This enclosure is in three parts insulated from each other. One part 16 embraces the cathode end 17 and neck 18 of the tube 3, another similar part 19 embraces the anode end 20 and neck 21 of the tube 3 while the remaining part 22 surrounds the central portion 23 of the tube 3 and overlaps the other parts 16 and 19 so that direct radiation is cut off excepting for that which emerges from a window 24 in the central part 22. The central part 22 of the enclosure is arranged to be at earth potential while the cathode end and anode end enclosures 16 and 19 are, as will be apparent from the following description, electrically so connected to the energising apparatus as to take up a potential approximately midway between the maximum potential of its respective tube terminal and earth.

The end enclosures 16 and 19 connect electrically, through the partition 14 on which they are mounted, to two metal casings 25 and 26 of two high tension transformers 5 and 4 mounted on the other side of the partition 14. The transformer casing 25 adjacent to the cathode end 17 of the X-ray tube 3 houses both a high tension transformer 5 and a tube filament transformer 27. The transformer casing 26 adjacent to the anode end 20 of the X-ray tube 3 houses only a high tension transformer 4. The leads from the various transformers 4, 5 and 27 pass to the X-ray tube electrodes 13 and 29, through the partition 14.

The supplies to the transformers 4, 5 and 27 are taken into the head by way of two high-tension cables 30 and 31 and plug and socket connections 32 and 33 on each side of the head 2. Actually, the head 2 is pivotally supported by a U-shaped bracket or gimbal 34 carried by a tubular horizontal arm 35 projecting from the pedestal 1 (see Figure 1) and the trunnions (not shown) of the head 2 are at the sides thereof so that the pivotal axis is at right angles to the length of the X-ray tube 3. The plug and socket connections 32 and 33 are disposed at the trunnions and the two cables 30 and 31 run up inside the tubular arm 35, one in each leg of the bracket 34, out through a suitable aperture (not shown), to the appropriate plug and socket connection 32 and 33. The U-shaped bracket 34 and tubular arm 35 are carried by a vertically moving slide 36 on the pedestal 1 as shown in Figure 1 and the bracket 34 and arm 35 can rotate through 360° about a horizontal axis at right angles to the direction of movement of the slide and can also move longitudinally of this axis. The two cables 30 and 31 pass into the pedestal 1 through the arm 35 and the slide 36 and there are, therefore, no trailing and unwieldy cables attached to the head 2.

Each high tension transformer 4 and 5 is an auto-transformer and one end of a transformer winding is connected to the anode 13 or the cathode 29 of the X-ray tube 3 as the case may be and the other to the transformer casing 26 or 25. Referring now to Figure 3 of the drawings in conjunction with Figure 2 and considering first the anode end 20 of the X-ray tube 3, the high tension cable 30 comprises two core conductors 37

and 38 insulated for 60 kv. D. C. between the core conductors 37 and 38 and the outer earthed braiding (not shown) but only for the normal A. C. supply voltage between the conductors 37 and 38, usually 250 volts. One conductor 37 is connected to the appropriate transformer casing 26 and the other to the tapping 39 on the high tension auto-transformer 4. At the other end of the cable and inside a casing 40 containing, in addition, a high tension D. C. generator 41, the cable is connected to the secondary winding 42 of a 1:1 ratio isolation transformer 43 the primary 44 of which is connected to the normal A. C. supply 45. This A. C. supply 45, through the high tension transformer 4 in the shockproof head 2, is arranged to generate a peak voltage of 50 kv. for the X-ray tube 3 when on load.

The conductor 37 of the high tension cable 30 is also connected to one side of a condenser 46 of the D. C. generator 41 mounted in the casing 40. The other terminal of the condenser 46 is earthed and the condenser 46 is arranged to be charged by a high tension transformer 47 supplied from the 250 volt A. C. supply 45. This transformer 47 comprises a primary winding 48, connected in parallel with a similar primary winding 49 supplying a similar high-tension D. C. generator 50 for the cathode end 17 of the X-ray tube 3, and a secondary winding 51 connected across the condenser 46 in series with a valve rectifier 52, the filament transformer (not shown) of which is also mounted in the casing 40. The D. C. generator 41 is arranged to provide a maximum of 60 kv. for the X-ray tube 3 and, as will be appreciated, the D. C. generator 41 works in series with the high-tension transformer 4 in the shockproof head 2 to provide a maximum peak of 110 kv. on load.

The cable arrangement 31 associated with the cathode end 17 of the X-ray tube 3 is similar to that associated with the anode end 20 but, in this case, a further core conductor 53 is provided for supplying the filament 29 of the X-ray tube 3, the filament supply using one of the main core conductors 54 as its other supply conductor; the A. C. filament supply 72 from the control desk (not shown) is also taken through an isolation transformer 55 and this transformer is mounted in the casing 56 containing the high-tension D. C. generator 50 associated with the cathode end 17 of the X-ray tube 3. A further transformer 57 for the filament circuit of the X-ray tube 3 is provided in the transformer casing 25 adjacent to the cathode end 17 of the X-ray tube 3 in the head 2.

Suitable means, operated from the control desk (not shown), are provided for controlling the filament current of the X-ray tube 3 and the output of both the D. C. generators 41 and 50 and the high tension transformers 4 and 5 in the shockproof head 2, the control of the latter can be so arranged that the peak high-tension A. C. voltage from the two transformers 4 and 5 together need never exceed the high-tension D. C. voltage from the two D. C. generators 41 and 50 and, therefore, the X-ray tube 3 need never act as a rectifier. However under certain conditions, a slight inverse voltage of 10 to 20 kv. across the tube 3 may not be undesirable.

From the above description, it will be appreciated that each D. C. generator 41 and 50 delivers a maximum of 60 kv. and the high-tension transformers 4 and 15 in the shockproof head 2, a peak of 50 kv. each, making a total maximum peak voltage of 220 kv.

The three isolation transformers 43, 55 and 58, are insulated for 60 kv. D. C. between their primary and secondary windings and the X-ray tube filament transformer 57 in the shockproof head 2 is provided with insulation for 50 kv. A. C. between its primary and secondary windings. Thus, by splitting up the high tension generation equipment for the X-ray tube 3 into a part within the shockproof head 2 and a part external to the shockproof head 2 such as within the pedestal 1, a considerable economy in the insulation of each component is effected. Since with this arrangement it is possible to maintain the spacings between the tube electrodes 13 and 29 and the tube shields 16, 19 and 20 and between the tube shields 16, 19 and 22 and the tank walls 7 of the head 2 at relatively small values. It also assists in reducing the space occupied by the X-ray tube, that is to say, the size of the head 2.

The two D. C. generator casings 40 and 56 are enclosed within the pedestal 1 by removable side covers 69 and 70 (Figure 1) and are arranged similarly as herein described, one on each side of the guideway 59. In Figure 4 one side of the pedestal 1 is partly removed to show one of the D. C. generator casings 40 in position, the other D. C. generator casing 56 being hidden by the side cover 70. Referring now to Figure 4 in conjunction with Figure 2, the vertically moving slide 36 on the pedestal 1, which slide carries the head 2, runs in suitable guideways 59 and two supporting cables 60 and 61 run from each side of the slide 36 vertically upwards to two pulleys 62 and 63 mounted one on each side of the path of movement of the slide 36. Each cable 60 or 61 passes over its pulley, 62 or 63 then downwards and under a pulley 64 or 65 fixed to one of the casings 40 or 56 containing the higher tension D. C. generator 41 or 50, and up again to a cable anchor 66 or 67 on a bracket 68 on the pedestal 1. Thus, there is one D. C. generator casing 40 or 56 hanging on each side of the path of movement of the slide 36 and each generator casing 40 or 56 is free to move up and down in the pedestal 1. The weight of each D. C. generator casing 40 or 56 and the equipments therein is arranged to be equal to the total weight of the slide 36 and the parts supported thereby and it will be appreciated that the weight of the D. C. generator casings 40 and 56 balances the weight of the slide 36 and its supported parts and that when the slide 36 moves, the casings 40 and 56 each move only half the distance the slide 36 moves. Naturally, the high tension cable 30 or 31 running from each D. C. generator 41 or 50 to the shockproof head 2 is so arranged in the pedestal 1 that the slide 36 is free to move up and down and the head 2 may rotate about and move longitudinally of the axis of the tubular arm 35 and U-shaped bracket or gimbal 34 supporting the shockproof head 2.

As the two D. C. generator casings 40 and 56 are so arranged that their range of movement is from the bottom of the pedestal 1 to about half-way up, a clear space is left at the top on each side of the path of movement of the slide 36 and these two spaces are occupied by the motor 71, pump 9 and cooler 10 of the oil cooling system, the motor 71 and pump 9 on one side and the cooler 10 on the other.

By arranging that the D. C. generator casings 40 and 56, and the equipments therein balance the weight of the shockproof head 2, the necessity of providing special balance weights is done away with and the total weight of the

equipment thereby reduced. Further, it will be appreciated that, by dividing the high tension generation equipment into two parts, part in the pedestal 1 and part in the shockproof head 2, the disadvantages of known deep therapy apparatus, referred to in the opening paragraphs of the specification, are avoided. Thus, since only a part of the total operating voltage is generated external to the shockproof head 2, high tension cables 30 and 31 may be used which are lighter than those used in the case where the total operating voltage is generated external to the head 2. The use of lighter cables 30 and 31 allows the adoption of the arrangement described above in which the cables run through the supporting means of the head 2. Obviously, the head 2 is considerably smaller and lighter in weight than those known constructions in which the head carries all the high tension generation equipment.

I claim:

1. A high voltage deep therapy X-ray apparatus operable from a normal low voltage alternating current source of electric energy in the order of 250 volts, for example, said apparatus comprising a shock-proof head, an X-ray tube operable at a high voltage of the order of 220 kv., means to mount said tube in said head, means to shiftably support said head, electrical equipment located within said head and operable from the low voltage alternating current source of electric energy for generating a substantial portion of the high operating voltage required by said tube, electrical equipment located external to and physically separate from said head and operable from the low voltage alternating current source of electric energy for generating the remaining portion of the operating voltage for said tube, said equipments being series-connected whereby to add the voltages generated thereby, and means to supply said low voltage alternating current source of electrical energy to both said equipments.

2. An X-ray apparatus according to claim 1 wherein both said equipments are divided into two parts whereof one part of each said equipments is associated with the cathode of the X-ray tube and the other part of each said equipments is associated with the anode of the X-ray tube so that the cathode of the tube is supplied with voltage from two series-connected parts each of which is from a different equipment and the anode of the tube is supplied with voltage from two series-connected parts each of which is from a different equipment.

3. An X-ray apparatus according to claim 1 wherein a housing is provided for the second-named equipment, wherein said housing is mounted for free vertical movement and wherein means is included to counterbalance said housing against the head.

4. A high voltage deep therapy X-ray apparatus operable from a normal low voltage alternating current source of electric energy in the order of 250 volts for example, said apparatus comprising a shock-proof head, an X-ray tube operable at a high voltage of the order of 220 kv., means to mount said tube in said head, means to shiftably support said head, high tension transformer equipment located within said head and operable from the low voltage alternating current source of electric energy for generating a substantial portion of the high operating voltage required by said tube, direct current generation equipment located external to and physically

separated from said head and operable from the low voltage alternating current source of electric energy for generating the remaining portion of the operating voltage for said tube, said equipments being series-connected whereby to add the voltages generated thereby and means to supply said low voltage alternating current source of electrical energy to both said equipments.

5. An X-ray apparatus according to claim 4 wherein both said equipments are divided into two parts whereof one part of each said equipments is associated with the cathode of the X-ray tube and the other part of each said equipments is associated with the anode of the X-ray tube so that the cathode of the tube is supplied with voltage from two series-connected parts each of which is from a different equipment and the anode of the tube is supplied with voltage from two series-connected parts each of which is from a different equipment.

6. An X-ray apparatus according to claim 4 wherein a housing is provided for the second-named equipment, wherein said housing is mounted for free vertical movement and wherein means is included to counterbalance said housing against the head.

7. A high voltage deep therapy X-ray apparatus operable from a normal low voltage alternating current source of electric energy in the order of 250 volts, for example, said apparatus comprising a shock-proof head, an X-ray tube operable at a high voltage of the order of 220 kv., means to mount said tube in said head, means to shiftably support said head, high tension transformer equipment located within said head and operable from the low voltage alternating current source of electric energy for generating as an alternating voltage a substantial portion of the high operating voltage required by said tube, direct current generation equipment located external to and physically separate from said head and operable from the low voltage alternating current source of electric energy for generating the remaining portion of the operating voltage for said tube, said equipments being series-connected whereby to add the voltages generated thereby and means to supply said low voltage alternating current source of electrical energy to both said equipments.

8. An X-ray apparatus according to claim 7 wherein both said equipments are divided into two parts whereof one part of each said equipments is associated with the cathode of the X-ray tube and the other part of each said equipments is associated with the anode of the X-ray tube so that the cathode of the tube is supplied with voltage from two series-connected parts each of which is from a different equipment and the anode of the tube is supplied with voltage from two series-connected parts each of which is from a different equipment.

9. A high voltage deep therapy X-ray apparatus operable from a normal low voltage alternating current source of electric energy in the order of 250 volts, for example, said apparatus comprising a shock-proof head, an X-ray tube operable at a high voltage of the order of 220 kv., means to mount said tube in said head, means to shiftably support said head, high tension transformer equipment located within said head for generating as an alternating voltage a substantial portion of the high operating voltage required by said tube, direct current generation equipment located external to and physically separate from said head for generating the remaining portion of the operating voltage for said tube, said equipments being series-connected whereby to add the voltages generated thereby, both said equipments being divided into two parts whereof one part of each said equipments is associated with the cathode of the X-ray tube and the other part of each said equipments is associated with the anode of the X-ray tube so that the cathode of the tube is supplied with voltage from two series-connected parts each of which is from a different equipment and the anode of the tube is supplied with voltage from two series-connected parts each of which is from a different equipment.

10. A high voltage deep therapy X-ray apparatus operable from a normal low voltage alternating current source of electric energy in the order of 250 volts, for example, said apparatus comprising a shock-proof head, an X-ray tube operable at a high voltage of the order of 220 kv., means to mount said tube in said head, means to shiftably support said head, high tension transformer equipment located within said head for generating as an alternating voltage a substantial portion of the high operating voltage required by said tube, direct current generation equipment located external to and physically separate from said head for generating the remaining portion of the operating voltage for said tube, said equipments being series-connected whereby to add the voltages generated thereby, a housing for the second-named equipment, means to mount said housing for free vertical movement, and means counter-balancing said housing against the head.
